US0D1111690S

(12) **United States Design Patent** (10) **Patent No.:** **US D1,111,690 S**
(45) **Date of Patent:** **** Feb. 10, 2026**

(54) **COOLER**

(71) Applicant: **Iris Ohyama Inc.**, Sendai (JP)

(72) Inventor: **Soma Okayama**, Kakuda (JP)

(73) Assignee: **Iris Ohyama Inc.**, Sendai (JP)

(**) Term: **15 Years**

(21) Appl. No.: **29/937,920**

(22) Filed: **Apr. 17, 2024**

(30) **Foreign Application Priority Data**

Oct. 18, 2023 (JP) ..... 2023-021658 D

(57) **CLAIM**

The ornamental design for a cooler, as shown and described.

DESCRIPTION

FIG. 1 is a front, top and left-side perspective view of a cooler showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof;

FIG. 7 is a left-side view thereof; and,

FIG. 8 is a front, top, and left-side perspective view thereof, shown in a state of use.

The broken lines shown represent portions of the cooler and form no part of the claimed design.

1 Claim, 8 Drawing Sheets
